KIER PILER

Robert W. Vose, West Springfield, Mass., assignor to Chicopee Manufacturing Corporation, Chicopee Falls, Mass., a corporation of Massachusetts

Application August 12, 1942, Serial No. 454,614

7 Claims. (Cl. 68—177)

This invention relates to an apparatus for arranging fabric in kiers or tanks, which apparatus is more commonly known as a kier piler.

In the processing of fabrics it is common practice to bleach and wash the so-called gray goods in large kiers or tanks and in so doing it is necessary that the fabric usually in the form of a "rope" be piled systematically in the kiers so as to permit the greatest possible amount of cloth to be treated at one time without becoming tangled and in such a manner as to permit thorough and even treatment of the cloth in its entirety.

Many attempts have been made in the past to provide suitable apparatus for piling the cloth in the tiers, but such devices have proven to be either cumbersome and bulky or prohibitively complicated.

It is the purpose of this invention to provide a simple and improved kier piler.

A better understanding of this invention will be had from consideration of the following drawings in connection with the following description and in which:

Figure 1 is a side elevation of a kier piler constructed in accordance with the invention and is illustrated in position over a kier;

Figure 2 is an end elevation of the same kier piler;

Figure 3 is a side elevation of the side opposite to that shown in Figure 1;

Figure 4 is an enlarged detail of the operating cam and associated parts; and

Figure 5 is a sectional detail of the bearing and slip ring construction.

As can be seen from the drawings, the entire apparatus is supported upon cross beams 1 which span the kier. These cross beams can be at any desired point above the kier, although for convenience in illustration Figure 1 shows the cross beams as being directly upon the top of the kier. It will also be apparent that if a battery of kiers are employed a single kier piler may be used to service all kiers and in such an installation the cross beams 1 would be mounted or travel upon tracks (not shown) positioned above the kiers to be served by the apparatus.

The kier piler itself consists of a feed tube or conduit 3 into which the fabric 4 in "rope" form is fed by any suitable means. Tube 3 is supported rotatably by a combination journal and thrust bearing 5, illustrated in more detail in Figure 5, and which retains the tube against downward movement while permitting rotation about its longitudinal axis. It will be understood that any

standard type of bearing capable of supporting the tube for rotation and carrying the vertical thrust may be employed. The fabric to be treated and piled in the kiers is fed through the entire length of the tube which serves as a feeding means for conducting the fabric to a main drum or pulley 7, rotatably supported by suitable bearings, in brackets 8 depending from a table or support 9, carried by the lower end of tube 3 so as to be rotatable therewith.

The entire assembly so far described is rotatable about a vertical axis and specifically the axis of the tube 3 and is positively rotated in the bearing 5 by means of a motor 11 driving reduction gearing 13 terminating in pulley 15, all carried by the cross beams 1, and which through belt 17 drives a pulley 19, mounted on the upper portion of tube 3.

As the rope of fabric emerges from the lower end of tube 3 it engages the lower portion or sector of the lower portion of the periphery of drum 7 mounted for rotation about a substantially horizontal axis. Although it is necessary only that the fabric engage a lower portion of the periphery of drum 7, i. e., a partial turn, it is preferred to cause the fabric to take one at least complete turn about the drum for security in driving for which purpose it is passed partially around drum 7 then around a transfer roll 21, rotatably supported by the arms 23, also depending from the table 9, and then back to and around drum 7. The transfer roll is mounted upon an axis inclined relatively to the axis of drum 7 so as to offset the fabric as it makes its complete turn about drum 7 and prevent any overlapping of the fabric.

Although the velocity and weight of the rope of fabric is sufficient to rotate drum 7, it is preferred to positively drive this roll independently of the rotation of the assembly about a vertical axis for which purpose a motor 25 is mounted upon table 9 and is energized through slip rings 27 (Figure 5) mounted in an insulating sleeve 29, carried by tube 3, and contacts 31, carried by an insulating collar 33. Motor 25 drives drum 7 through a belt 35 traveling over a pulley 37 on the motor shaft, and a pulley 39 on the drum shaft.

The point of departure of the fabric from the drum 7 and thereby the piling of the fabric in the kier is controlled by a tangent roll 41, carried by arms 43 pivoted about the axis of drum 7. The tangent roll is spring urged or "loaded" into contact with the drum 7 by springs 45. By oscillating arms 43, the position of tangent

roll 41 may be varied about the periphery of drum 7 and accordingly the point of departure of the fabric 4 from drum 7 may be varied depending upon the position of roll 41. This and the velocity of travel of the fabric will determine the manner in which the fabric is piled in the kier.

In order to vary the position of the tangent roll 41, and cause the fabric to be piled as illustrated in Figure 1, one of the arms 43 is connected by a link 47 to one end of an arm 49, the other end of which is secured to a cam follower shaft 51 which is also rigidly fastened to cam follower 52 which engages a heart-shaped cam 53 secured to cam shaft 54. Cam shaft 54 also carries a pulley 55 driven by a belt 56 engaging a pulley 57 on the drum shaft. The linkage and cam just described for variably positioning the tangent roll is so designed as to cause proper movement of arms 43 and tangent roll 41 as to cause the fabric to be piled radially of the kier, one form of piling being shown in Fig. 1. As the entire unit is rotated the fabric will be piled over the entire kier floor. Obviously different cams and linkage can be employed to cause a different throw of the fabric.

From the foregoing, it will be seen that as a rope of fabric is fed into conduit 3 it descends through the conduit and engages drum 7, taking one complete turn therearound passing under tangent roll 41 which through heart-shaped cam 53 controls the point of departure of the fabric. The position of tangent roll 41 is constantly varied as the entire device is rotated about the axis of conduit 3 thus causing the cloth to be piled evenly and throughout the entire kier without tangling. It can also be seen from the foregoing that inherently the foregoing mechanism can be used to pile the fabric in the kier in at least two ways. If the linear travel or velocity of the fabric, in feet per second for example, is equal to the product of the number of complete oscillations per second of the tangent roll and twice the radius (i. e., the diameter) of the kier, the fabric will be laid or folded as shown diagrammatically in Fig. 1. On the other hand if the velocity of the fabric is greater, the fabric will be piled substantially evenly over the entire kier floor as before, but the fabric will be in bunched or crowded radial folds rather than in folds or layers of a single thickness or lamination. The foregoing mechanism is comparatively simple in construction and comparatively light in weight so that it is portable and can readily be moved from one kier to another.

It will be obvious to those skilled in the art that minor changes may be made in the details of construction without departing from the spirit and scope of the invention as defined in the appended claims.

I claim:

1. In a kier piler, adapted to be positioned over a kier, a rotatable drum, means for feeding fabric to and around said drum, a transfer roll for offsetting the fabric as it passes around said drum, a tangent roll movable about the lower portion of the periphery of said drum and arranged to hold the fabric to said drum in contact therewith and control its point of leaving said drum, and means for continuously varying the position of said tangent roll about the periphery of said drum whereby fabric fed to said drum will be piled evenly in the kier over which said piler is positioned.

2. In a kier piler, adapted to be positioned over a kier, a rotatable drum, means for feeding fabric

to and around said drum, a transfer roll for offsetting the fabric as it passes around said drum, a spring-loaded tangent roll movable about the lower portion of the periphery of said drum and arranged to hold the fabric in said drum in contact therewith and control its point of leaving said drum, and means for continuously varying the position of said tangent roll about the periphery of said drum whereby fabric fed to said drum will be piled evenly in the kier over which said piler is positioned.

3. In a kier piler, adapted to be positioned above a kier, a rotatable drum mounted for rotation about its horizontal axis and about a vertical axis, means for feeding fabric to and around a portion of said drum, a tangent roll movable around the lower portion of the periphery of said drum and arranged to hold the fabric fed to said drum in contact therewith and to control its point of leaving said drum, means for continuously varying the position of the tangent roll about the periphery of the drum, and means for rotating said drum and said tangent roll about said vertical axis while said fabric is fed to and around said drum whereby fabric fed to said drum will be piled evenly throughout the entire kier.

4. In a kier piler, adapted to be positioned over a kier, a rotatable table mounted for rotation about a vertical axis, means for rotating said table about said vertical axis, a rotatable drum on said table, means for rotating said drum independently of rotation of said table and during rotation of said table, means for feeding fabric to and around a portion of said drum, a tangent roll movable about the lower portion of the periphery of said drum and arranged to hold the fabric fed to said drum in contact therewith and to control its point of leaving said drum, and means for continuously varying the position of said tangent roll about the periphery of said drum whereby fabric fed to said drum will be piled evenly throughout the entire kier.

5. In a kier piler, adapted to be positioned over a kier, a rotatable drum mounted for rotation about its horizontal and also about a vertical axis, means for feeding fabric to and around said drum, a transfer roll for offsetting the fabric as it passes around said drum, a tangent roll movable about the lower portion of the periphery of said drum and arranged to hold the fabric fed to said drum in contact therewith and to control its point of leaving said drum, means for simultaneously rotating said drum about said two axes, while said fabric is fed to and around said drum, and means for continuously varying the position of said tangent roll about the periphery of said drum whereby fabric fed to said drum will be piled evenly throughout the entire kier.

6. In a kier piler, adapted to be positioned over a kier, a rotatable drum mounted for rotation about its horizontal and a vertical axis, means for feeding fabric to and around a sector at least of said drum, a tangent roll movable about the periphery of said drum and arranged to hold the fabric fed to said drum in contact therewith and control its point of leaving said drum, means for continuously varying the position of the tangent roll about the lower periphery of the drum, means for rotating said drum and said tangent roll about said vertical axis, and means for simultaneously rotating said drum about its horizontal axis whereby fabric fed to said drum will be piled evenly throughout the entire kier.

7. In a kier piler adapted to be positioned over

a kier, a rotatable drum mounted for rotation about its horizontal and a vertical axis, means for positively and simultaneously rotating said drum about its two axes, means for feeding fabric to and around said drum while the latter is being rotated about said two axes, a transfer roll for offsetting the fabric as it passes around said drum, a spring-loaded tangent roll movable around the lower portion of the periphery of said

drum and arranged to hold the fabric fed to said drum in contact therewith and control its point of leaving said drum, and means for continuously varying the position of the tangent roll about the periphery of said drum whereby fabric fed to said drum will be piled evenly throughout the entire kier.

ROBERT W. VOSE.

CERTIFICATE OF CORRECTION.

Patent No. 2,386,371.

October 9, 1945.

ROBERT W. VOSE.

It is hereby certified that error appears in the printed specification of the above numbered patent requiring correction as follows: Page 1, second column, line 17, for "pliley" read --pulley--; page 2, second column, line 64, claim 6, after "of" insert --the lower portion of--; line 65, same claim, before "periphery" insert --lower portion of the--; and that the said Letters Patent should be read with this correction therein that the same may conform to the record of the case in the Patent Office.

Signed and sealed this 1st day of January, A. D. 1946.
